UNITED STATES PATENT OFFICE

OWEN J. McGANN, OF PITTSBURG, PENNSYLVANIA, ASSIGNOR OF ONE-HALF
TO JOHN C. PENNIE, OF WASHINGTON, DISTRICT OF COLUMBIA.

DESIGN FOR A WATER-CLOSET BOWL.

SPECIFICATION forming part of Design No. 18,192, dated March 20, 1888.

Application filed November 16, 1887. Serial No. 255,369. Term of patent 7 years.

To all whom it may concern:

Be it known that I, OWEN J. McGANN, a citizen of the United States, residing at Pittsburg, in the county of Allegheny and State of Pennsylvania, have invented certain new and useful 5 Improvements in Designs for Water-Closet Bowls; and I do declare the following to be a full, clear, and exact description of the invention, such as will enable others skilled in the 10 art to which it appertains to make and use the same, reference being had to the accompanying drawings, and to the letters and figures of reference marked thereon, which form a part of this specification.

15 My invention relates to a new and original design in water-closet bowls, of which the following is a specification, reference being had to the accompanying photographic views, forming part thereof.

20 In said views, Figure 1 represents a side elevation of my newly-designed water-closet, bowl, and Fig. 2 represents a front elevation thereof.

The leading features of my design consist of 25 a base, A, a middle portion, B, springing from

said base and having an upwardly-projecting curvature at C D, and a top portion, E, substantially hemispherical in conformation, springing from the said middle portion, the water-closet bowl from top to base presenting an integral uninterrupted wall-surface. 30

My new design, when viewed in side elevation, as shown in Fig. 1, has an appearance similar to that of a truncated human figure in a squatting position, wherein the upper portion, E, would represent the abdomen, the 35 curve D the buttocks, and the curve C the knee-joint.

What I claim is—

The design for a water-closet bowl shown 40 and described, having the general configuration of a truncated human figure in a squatting position.

In testimony whereof I affix my signature in presence of witnesses.

OWEN J. McGANN.
